UNITED STATES PATENT OFFICE.

JERVIS R. HARBECK, OF DETROIT, MICHIGAN, ASSIGNOR TO DETROIT CAN COMPANY, OF DETROIT, MICHIGAN, A CORPORATION OF MICHIGAN.

PROCESS OF MANUFACTURING PROOFED PAPER TUBES.

1,173,266.

Specification of Letters Patent.

Patented Feb. 29, 1916.

Application filed January 23, 1911. Serial No. 604,144.

To all whom it may concern:

Be it known that I, JERVIS R. HARBECK, a citizen of the United States, residing in Detroit, in the county of Wayne and State 5 of Michigan, have invented a new and useful Improvement in Processes of Manufacturing Proofed Paper Tubes, of which the following is a specification.

My invention relates to improvements in 10 the manufacture of proofed paper tubes or bodies for cans.

Heretofore in the manufacture of water-proofed paper tubes or bodies, those designed to be impervious to passage of liquid or gases, 15 it has been customary to apply or introduce the asphaltum or waterproofing compound in a heated and liquid condition between successive layers or coils of the paper body, or else to introduce it in a dry and powdered 20 form between successive layers, and then subject the paper body to heat to fuse the asphaltum or waterproofing compound. Both these methods are more or less objectionable, and slow, expensive and uncertain 25 in operation, and both require a relatively large amount of asphaltum or proofing compound to be used, as it is applied directly to the porous and relatively coarse and thick 30 paper or fibrous material of which the body or tube is made, and both require special machines or appliances, the former being liable to gum up and interfere with the operation of the body making or tube winding machine and the latter requiring a special 35 heating and fusing step which may be more or less uncertain or defective in rendering the paper or fibrous body completely impervious to passage of liquids or gases.

The object of my invention is to provide 40 an improved method or process of manufacturing waterproofed or liquid and gas proofed paper or fibrous can bodies or tubes, by use of which the difficulties heretofore experienced may be overcome, the water-proofed bodies or tubes manufactured very 45 rapidly and cheaply and rendered thoroughly impervious to passage of liquids or gases, and with a relatively small amount of asphaltum or proofing material, and 50 without the necessity of special machines or appliances. The method or process I employ to practically accomplish this object or result, and this constitutes my invention, 55 consists in introducing between the successive coils or layers of the paper or other

fibrous material of which the body or tube is formed, an extremely thin, dry, solid, flexible, continuous film of asphaltum or proofing compound supported and embraced between two layers of thin, close 60 paper which are firmly united thereto and secured together thereby, the thin paper exterior coating of the asphaltum or proofing film adapting it to be glued or adhesively united on both faces thereof to the coils or 65 layers of tube-material with which it contacts, both the tube-material webs and the composite proofing material web being spirally wound, the proofing material web forming one thickness or layer, and the tube- 70 material web or webs forming as many inner or outer thicknesses or layers as may be desired.

In practising my invention, the paper or tube-material webs are wound spirally 75 around a forming mandrel, and the proofing member web is also wound spirally, one of its faces being coated with adhesive material to adhesively unite it to the inner layer of tube-material web upon which it is wound, 80 and the superposed web of tube-material having one of its faces coated with adhesive so that the proofing member web or layer is adhesively united on both its faces to the 85 layers of tube-material between which it is interposed.

Any suitable spiral tube winding machine known to those skilled in the art may be used in practising my invention.

In the accompanying drawing forming a 90 part of this specification, to enable my invention to be more fully understood and readily practised by those skilled in the art, I have shown at Figure 1 a longitudinal section of a proofed, laminated paper body or tube as produced by my process. Fig. 2 is a cross section on line 2—2 of Fig. 1. Fig. 3 is a plan view, showing a short piece of the proofed paper tube and the tube-material and proofing webs of which it is formed by 95 my invention. Fig. 4 is a detail, plan view representing a form of spiral winding tube machine suitable for use in practising my invention and Fig. 5 is an enlarged, detail 100 cross section of the proofing member layer or web.

In the drawing, 1 represents a proofed, 105 spirally wound paper tube which may be cut into suitable lengths to form can bodies 2, as shown in Fig. 1. The proofed tube 1 110

is composed preferably of a spirally wound inner layer 3 formed from the tube-material web 4, an intermediate spirally wound proofing member layer 5 formed from the proofing member web 6 and an outer spirally wound layer 7 formed from the tube-material web 8. The proofing member layer 5 and the web 6 from which it is formed is composed of a solid flexible film of asphaltum or 10 proofing compound 9 embraced and compressed between and rigidly secured to thin supporting paper or fibrous layers 10, 11 on the opposite faces of the proofing compound film. The thin paper or fibrous layers 10, 11 15 of the proofing compound film 9 adapt the proofing member web to be adhesively united to the tube-material layers 3, 7, between which it is interposed by the adhesive coating applied to one face of the tube-material web 4, and also to one face of the proofing member web 6.

In Fig. 4 of the drawing, 12 represents the mandrel or former around which the spirally wound proofed paper tube is formed 25 and 13, 14 the diagonally arranged feed belts which serve to rotate and feed or advance the spirally wound paper tube as it is formed from the webs of tube-material 4, 8, and the intermediate proofing member 30 6 which are fed to the mandrel at an angle by their guide and feed devices 15, 16, 17, one for each web.

In the drawing, the relative thickness of the tube-material layers and proofing member layer is exaggerated for greater clearness of illustration, and this applies specially 35 to the proofing film and the fibrous layers united thereto, all of which in practice are extremely thin.

40 I claim:—

1. The herein described process for making paper container bodies, which consists in applying to a layer of thin porous paper

a thin film of fused cement to form a thin compound proofing sheet adapted to be 45 glued or adhesively united to a layer of tube material, and then uniting such compound proofing sheet adhesively and by a winding process to a sheet of paper tube material, to form a proofed and impervious container 50 body.

2. The herein described process for making paper container bodies, which consists in uniting two layers of thin porous paper with a thin interposed film of a fused cement to form a thin compound proofing sheet 55 adapted to be glued or adhesively united to a layer of tube material, and then uniting such compound proofing sheet adhesively and by a winding process to a sheet of paper 60 tube material, to form a proofed and impervious container body.

3. The herein described process for manufacturing wound and proofed paper container bodies, consisting of a plurality of 65 successive coils, which consists in first preparing a proofing member or film by inclosing a thin flexible and continuous film of fused proofing compound between two layers of thin porous paper which are firmly 70 united thereto and secured together thereby, the thin paper exterior coating of the proofing film adapting it to be adhesively united on both faces thereof to the coils or layers of tube material with which it is to contact; 75 and then introducing the said thin proofing member between successive layers or coils of paper tube material, and adhesively uniting the said proofing member to the layers of the tube material between which it is interposed.

JERVIS R. HARBECK.
